UNITED STATES PATENT OFFICE.

ELIHU THOMSON, OF NEW BRITAIN, CONNECTICUT, ASSIGNOR TO THE THOMSON-HOUSTON ELECTRIC COMPANY, OF CONNECTICUT.

CUT-OUT APPARATUS FOR ELECTRIC LAMPS.

SPECIFICATION forming part of Letters Patent No. 350,955, dated October 19, 1886.

Application filed December 18, 1883. Serial No. 114,967. (No model.)

To all whom it may concern:

Be it known that I, ELIHU THOMSON, a citizen of the United States, and a resident of New Britain, in the county of Hartford and State of Connecticut, have invented certain new and useful Improvements in Cut-Out Apparatus for Electric Lamps, of which the following is a specification.

My invention relates to apparatus for providing a branch circuit around an electric lamp, either automatically or by hand, when for any reason it becomes necessary or desirable to form such circuit in order to preserve the continuity of the general circuit upon which the lamp is placed.

The object of my invention is to provide an efficient means whereby a branch or safety shunt may be automatically formed and preserved around an electric-arc lamp in case through any derangement of the lamp the carbons fail to feed, and the arc therefore becomes abnormally long.

My invention is also designed to afford a means whereby the branch or safety circuit may be readily closed by hand, and may at any time be opened after having been formed, either automatically or by hand.

My invention consists in placing above or in proximity to the arc a conductor connected with the general circuit, so that the transfer of arc or current to said conductor or the closing of a circuit by the impingement of arc upon said conductor will close a circuit through an electro-magnet or other device, and will thus cause the direct or indirect actuation of the circuit-closer, whereby the branch or safety circuit may be closed around the lamp. The electro-magnet thus energized may be in the branch or safety circuit formed, and its armature may actuate directly the contacts for closing the same, so that the force of the magnet will tend to keep the circuit closed. While the safety-circuit is thus closed it may be desirable to open the same, and to allow this to be done I provide an extra or supplemental switch, (that may be, if desired, a hand-switch,) which is arranged so that it may complete a shunt around said magnet, thus causing the armature of the latter to fall back and open the safety or branch circuit.

In order to permit the lamp to be extinguished at will, I provide an extra switch, to be operated, preferably, by hand, and suitably arranged and connected to close the circuit through the said magnet, which, being energized, draws forward its armature and completes and holds closed the safety or branch circuit until said branch is opened through the shunting of the magnet by the hand-switch first mentioned or through other means.

The hand-switch just described for putting out the lamp may be arranged in any convenient place, either in the same apartment with the lamp or in another location, and may be connected with said magnet by fine and almost invisible wires.

Figure 1 of the accompanying drawings illustrates my invention diagrammatically. Fig. 2 illustrates one form of mechanism which I prefer to employ with ordinary or non-focusing arc-lamps for keeping in proper position the conductor by which the elongated arc closes a circuit for causing the safety or branch circuit to be formed.

C' C indicate the carbons of an electric lamp, and A a conductor of any suitable kind connected with the general circuit on one side of the carbons by a wire, 5, and arranged above the arc, so that upon the formation of an abnormally long arc a transfer of arc to said conductor will take place, or by the highly-conducting heated products of the arc a circuit will be closed between said conductor and a ring of metal or other form of conductor, B, thus closing a circuit from the point 7 of the main conductor to the point 6 in the other side of the arc. In this circuit is placed an electro-magnet, C, or other suitable device by which the closing of the ordinary safety or branch circuit may be effected. In the present instance the branch is closed by the armature-lever of said electro-magnet, which is drawn toward the magnet and impinges against a contact. The safety branch thus closed includes the electro-magnet, which latter thus acts to keep the said branch intact.

D indicates a hand-switch by which the magnet C may be momentarily shunted, so that its armature-lever may fall back and break the safety-circuit, and thus put the apparatus into

condition to permit the lamp to resume its operation.

When it is desired to put out the lamp, a switch, E, is employed connected with the magnet C and the general circuit by the wires *a a*, as shown, so that the completion of the circuit between *a a* will cause the magnet C to become energized and its armature thereby to close and hold closed the safety or branch circuit around the lamp. The switch E may be placed at any convenient or desirable point either near to or remote from the lamp. It may be operated by a cord, F, or otherwise, and is by preference a self-opening switch, as indicated, made self-opening by a spring, e.

The conductor A may be supported in any desired manner, as also may the ring B. If the carbon slides through the ring, there may obviously be contact between them, in which case the magnet should be placed in the circuit from A, as is shown in Fig. 2. If the lamp is a focusing lamp, the conductor A may be stationary; but if the lamp is non-focusing it should be made to feed downward with the burning of the carbon, so as to be always in proper relation to the arc. This may be effected by the arrangement shown in Fig. 2, where G indicates a wheel gearing with the carbon or carbon-carrier, and having on its shaft a pinion, H, that gears with the rack-bar K, supporting the conductor A. The pinion is of proper size relatively to wheel G to lower the parts at the rate at which the arc shifts downward.

The conductor A consists either of a ring or of one or more downwardly-depending conducting-pins insulated from and supported by a ring, B, which latter is carried by the rack and is in connection with the positive side of the lamp by means of said rack and by reason of its contact with the carbon sliding through it.

The conductor A is in connection with the negative side of the lamp by means of the rod or stem L, which is attached to the conductor A, and against which rod bears the insulated spring M, connected with the negative side of the lamp through the electro-magnet C, as indicated. The contact closed by the armature of said magnet serves in obvious manner to complete and preserve a branch around the arc and through the magnet.

The other devices herein described are omitted from the drawings, as are also the ordinary parts of an electric lamp, for the sake of simplicity.

I do not limit myself to the form of the conductor A, the gist of the invention consisting in arranging and connecting the same so that the enlarged arc will by means of said conductor close a circuit, by which a shunting or cutting out of the lamp may be effected.

What I claim as my invention is—

1. The combination, with an electric lamp, of a branch or safety circuit, a magnet in said branch or safety circuit, a circuit-closer acted upon in opposite directions by said magnet,

and a suitable retractor, so as to be held closed by the attraction of said magnet and to be opened by the falling away of the magnet's armature under the influence of the retractor when the magnet loses its power, and a switch for completing a shunt around said magnet, whereby the safety circuit may be opened.

2. The combination, with an electric lamp, of a branch or shunt circuit around the lamp, an electro-magnet in said shunt for holding the same closed, and a supplemental hand-switch connected with said magnet for closing the circuit through the same, whereby the same may be energized to close the shunt contacts.

3. The combination, with an electric lamp, of a conductor placed near the arc and connected with one side of the lamp, as described, whereby an abnormal lengthening of the arc current will flow across the space between an electrode and said conductor, and a circuit containing devices whereby a safety or shunt or branch may be closed around the lamp upon the closing of said circuit through the conductor by an abnormally long arc, as and for the purpose described.

4. The combination, in an electric lamp, of a conductor, which is placed near the arc and closes the safety-circuit of a switching device when the arc is transferred thereto, and means for moving said conductor correspondingly with the shifting in position of the arc by consumption of the electrodes, so that the conductor may be kept in the same position with relation to the arc.

5. The combination, with safety switch appliances in an electric-arc lamp, of a conductor in continued proximity to the electric arc and connected with one side of the lamp, as described, whereby on abnormal lengthening of the arc a current will flow from one electrode to said conductor across the space between them.

6. The combination, with an electric lamp, of a conductor placed near the arc, and a safety-shunt or branch-circuit closer controlled by the action of the current passing across the space between said conductor and a lamp-electrode upon the formation of an abnormally long arc.

7. The combination, with the movable and fixed electrodes, of a support for a device to be carried in continued proximity to the arc, and interposed controlling mechanism interposed between said support and the movable electrode, proportioned in the manner described to permit the support to move at a rate corresponding to the shifting in position of the arc by consumption of the fixed and movable electrodes.

Signed at Boston, in the county of Suffolk and State of Massachusetts, this 13th day of December, A. D. 1883.

ELIHU THOMSON.
